UNITED STATES PATENT OFFICE.

MATTHEW VIERENGEL, OF BROOKLYN, NEW YORK, ASSIGNOR TO M. VIERENGEL MACHINE CO., INC., OF NEW YORK, N. Y., A CORPORATION OF NEW YORK.

DRINKING CUP.

Application filed February 16, 1927. Serial No. 168,546.

My present invention relates to a drinking cup and more particularly to that type of drinking cup made of paper or other similar material and foldable to assume a normally flat position and the parts of which are adapted to be spread or separated for use. I am aware that heretofore various forms of this type of drinking cup have been made and used, examples of these are that type in which the cup is formed to comprise obverse and reverse members having substantially parallel sides and provided with flaps by which the cups may be removed from a superimposed pile thereof; that type in which the cup is constructed to taper from a relatively narrow closed end to a relatively wide opened end; and that type in which a parallel sided cup has been provided at the open end thereof with a spout for the supposed purpose of aiding or directing the liquid in its flow from the cup in the use thereof. In this and other similar forms of foldable drinking cups made of paper and similar material there is more or less difficulty as well as inconvenience in the use thereof. Oftentimes, due to the set formed in the paper by the piling and packing of the cups they do not readily open as intended; obviously in that type of cup in which the sides taper from a relatively narrow closed end to a relatively wide opened end there is a tendency of the liquid to flow too fast from the cup in the use thereof. Furthermore, in the construction of drinking cups of this type, the flaps which are employed to close the cup are folded in such a manner that the seam is of varying numbers of piles of material from which the cup is formed, thereby making the pile of cups when placed together thicker in certain portions than others which is an obvious disadvantage in packing the cups.

The object of my invention is to overcome these difficulties and to provide a cup of the type to which the invention relates in which there is a relatively wide closed end and a relatively narrow open end, the open end being preferably provided with an extension for directing the flow of the liquid from the cup to the mouth of the user whereby as will be appreciated due to the taper of the cup the flow of the liquid is more or less retarded and in any event does not rush from the cup to the mouth of the user. Furthermore, in carrying out the invention the blank from

which the cup is formed is so constructed that the flaps, by which when folded the closed end of the cup is formed, provide a uniform thickness of the seams by which the closed joint in the cup is made. Still furthermore, in carrying out the invention, the adhesive is so applied to the corners of the interfold flaps as to insure a liquid tight joint at the closed end of the cup. These and other features of the drinking cup made in accordance with the present invention will be hereinafter more particularly described. When formed, my cup presents substantially similar reverse and obverse sides of trapezoidal shape, the bottom closed end of the cup being the base of the trapezoid and being the longer of the two parallel sides of the trapezoid, the shorter opposite side defining the open top end of the cup. The opposite lateral edges of the obverse and reverse sides, defining the two other opposite lateral sides of the trapezoids, substantially converge toward each other as they extend from the bottom to the top of the cup, which results in forming a receptacle in which the width of the obverse and reverse faces, at the top open end of the cup, are substantially less than the width of these faces at the bottom closed end.

As the result of the shape and combination of the parts forming my cup, when in use, the obverse and reverse faces diverge from each other as they extend upwardly from the closed bottom to the open top, the points of greatest divergence of these faces being at the edges defining the open top end of the cup.

In the drawing Figure 1 is a perspective view illustrating a drinking cup made in accordance with this invention.

Fig. 2 is a plan of a blank from which the cup is constructed.

Fig. 3 is a plan showing the parts of the blank partially folded to position.

Fig. 4 is a plan showing the parts completely folded to position.

Fig. 7 is a section on line 7—7, Fig. 4.

Fig. 8 is a partial elevation showing another form of blank, and

Fig. 9 is an elevation of the closed end of a cup when made in the form of the cup illustrated in Fig. 8. 105

Referring to the drawing and particularly

to Figs. 1 to 7 inclusive, the drinking cup made in accordance with this invention is formed from a blank of suitable paper or other material in such a manner as to taper appreciably from a relatively broad closed end to a relatively narrow open end. The blank from which the cup is made is preferably formed as illustrated in Fig. 2. This includes a reverse side 10 and flaps 11 and 12 forming an obverse side of the cup. These parts are spaced with their limitations determined by fold lines 13 and 14. One end of the blank is provided with an extension at the corresponding end of the reverse side 10 and the adjacent edge portions of the flaps 11 and 12 are cut away substantially as illustrated in this figure of the drawing in order that when folded to position a lip 15 is provided at the open end of the cup for directing the flow of the liquid from the cup to the mouth of the user or otherwise as may be desired for example in pouring liquid from the cup.

At the opposite end of the blank the reverse side 10 is extended to provide a flap 16 and the corresponding ends of the flaps 11 and 12 are extended to provide flaps 17 and 18. Also as illustrated in this figure, the opposite ends of the flap 16 merge with the adjacent ends of the flaps 17 and 18, that is the flaps 17 and 18 form continuations of the flap 16 and are not separated or divided therefrom.

In forming the blank in addition to the fold lines 13 and 14 which may be formed by suitably creasing the material, the blank is also provided with a fold line 19 at the flap end of the reverse member, and fold lines 20 and 21 at the flap ends of the flaps 11 and 12. In folding the parts of the blank to position the flap 11 is first folded over on the line 13 and the flap 12 then folded on the line 14 so that the parts then assume a position as illustrated in Fig. 3, in which the fold line 20 is in alignment with the fold line 19 and also the fold line 21 is in alignment with the fold line 19. At this point in the description it is to be noted that the flap end of the flap 11 is cut away as indicated at 22 and the adjacent end of the flap 17 as indicated at 23, while correspondingly the flap end of the flap 12 is cut away as indicated at 24 and the adjacent end of the flap 18 as indicated at 25. The outer extremity of the fold line 20 terminates in this cut away portion of the flaps 11 and 17 as indicated at 26, and the outer end of the fold line 21 terminates in the cut away portion of the flaps 12 and 18 as indicated at 27. The construction is such that when the parts are folded as hereinbefore described the ends of these fold lines 20 and 21 assume a superimposed position, that is the end 27 of the fold line 21 is superimposed on the end 26 of the fold line 20 in a point as indicated at 28 for a purpose which will presently appear.

The edge portion of the flap 12 is provided

with a suitable adhesive material as indicated at 29, and the flap 16 is provided with an adhesive material as indicated at 30 which is extended across and made to cover adjacent portions of the flaps 17 and 18 as indicated at 31 and 32 respectively. It will now be understood that in making the fold as hereinbefore described the adhesive material 29 on the flap 12 connects this flap to the flap 11 and that the adhesive material on the flaps 17 and 18 overlies the adhesive material on the adjacent surface of the flap 16 and provides what may be termed a double supply of adhesive to these superimposed portions of the flaps to assist in insuring a liquid tight joint at the closed end of the cup. The other portions of the flaps 17 and 18 are also caused to adhere to the adjacent or underlying portions of the flap 16 due to the fact that the flap 16 in its substantial entirety is provided with the adhesive material.

In completing the closure the flaps 16, 17 and 18 are folded on a line 33 which is coincident with the then superimposed fold lines 19, 20 and 21. This causes that portion of the gummed or adhesived inner surface of the flap 16 which then extends beyond the edges of the flaps 17 and 18 to adhere to the outer underlying surfaces of the flaps 11 and 12. It will now be understood that because of the cut away ends of the flaps 11 and 17 and the correspondingly cut away ends of the flaps 12 and 18 that portion 23 of the cut away end of the flap 17 conforms substantially with the cut away end portion 24 of the flap 12, and correspondingly the cut away end portion 25 of the flap 18 corresponds substantially with the cut away end portion 22 of the flap 11 so that in this portion of the joint there are only three plies in all parts thereof, and that when the flap 16 is finally folded to place that portion of the joint made by the overlapping flaps consists in substantially all of its parts of four plies of the material. This is illustrated in Fig. 6. As shown in Fig. 7, however, of course, that portion of the joint lying exteriorly of the flaps 17 and 18 is merely of three plies of the material, whereby as hereinbefore stated, the joint forming the liquid proof closure at the closed end of the cup is of substantially uniform thickness.

In this form of the invention the end portions of the flap 16 are so formed that when the flap 16 is turned to place these end portions lie substantially parallel with the corresponding edges of the cup as is clearly indicated in Fig. 4 of the drawing. In some instances, however, as shown in Figs. 8 and 9, the end portions of the flap 16 may be extended as indicated at 34 and 35 and after the flap 16 is folded to position these end portions 34 and 35 thereof may be turned over the tapering edge portions of the obverse and reverse members of the cup and secured to the

underlying adjacent surface of the reverse side of the cup. This feature, however, is a detail of construction which is no necessary part of the invention.

As illustrated in the drawing the reverse member 10 is provided with a crease line 38 extending in a substantially centrally disposed position from the open end of the cup an appreciable distance toward the closed end of the cup. This may be provided to cause the cup to more readily open by compressing the tapering side edges thereof. It will be understood, however, that this crease line may be dispensed with or instead of being placed in the reverse side or member may be placed in the obverse side or member with the same results.

I claim as my invention:

1. A drinking cup formed from a blank of foldable material and comprising a reverse member, an obverse member having overlapping and connected parts which when turned to position conform to the reverse member, flaps extending from corresponding ends of the reverse member and the parts of the obverse member and adapted to be folded over upon and connected to themselves and the adjacent outer faces of the parts of the obverse member to form a relatively wide closed end at one extremity of the cup from which the cup tapers to a relatively narrow open end, the adjacent portions of the parts of the obverse member and the flaps extending therefrom being so cut that when the flaps are folded over on each other the joint formed by the flaps is made of a substantially uniform number of plies throughout.

2. A drinking cup formed from a blank of foldable material and comprising a reverse member, an obverse member having overlapping and connected parts which when turned to position conform to the reverse member, flaps extending from corresponding ends of the reverse member, and also from the obverse member, which flaps are adapted to be folded over upon and connected to themselves and to the adjacent outer faces of the parts of the obverse member to form a closed end at one extremity of the cup, the adjacent portions of the parts of the obverse member and the flaps extending therefrom being so cut that when the flaps are folded over on each other the joint formed by the flaps is made of a substantially uniform number of plies throughout.

3. A drinking cup of foldable material, comprising a substantially flat, trapezoidally shaped reverse member, a substantially flat, trapezoidally shaped obverse member, consisting of flaps integral with and folded transversely over said reverse member from the opposite longitudinal sides thereof and united along their overlapping edges, and a flap closing the base of said cup, integral with and folded longitudinally over said reverse

member from the base thereof and overlapping and united to the base of the obverse member.

4. A drinking cup of foldable material, having a closed bottom and an open top, comprising a substantially flat, trapezoidally shaped reverse member, a substantially flat, trapezoidally shaped obverse member, consisting of flaps integral with and folded in a single fold transversely over said reverse member from the opposite longitudinal sides thereof and united along their overlapping edges, and a flap closing the base of said cup, integral with and folded in a single fold longitudinally over said reverse member from the base thereof and overlapping and united to the base of the obverse member, the upper marginal edges of the reverse and obverse members being of convex and concave outline, respectively.

5. A blank of foldable material for a drinking cup, comprising a reverse member, the sides and bottom of which are confined, respectively, by the sides and base of a trapezoid, two side flaps, which extend from the sides of said reverse member, which are of such width that they overlap each other above said reverse member when they are overfolded along the sides of said reverse member, and which are of such length at their lower ends that they overlap the bottom of said reverse member, when they are overfolded along the sides of said reverse member, a base flap extending from the bottom of said reverse member, and adhesive means on one side of said base flap and on those parts of said side flaps which overlap each other when folded over said reverse member.

6. A blank of foldable material for a drinking cup, comprising a reverse member, the sides and bottom of which are confined, respectively, by the sides and base of a trapezoid, two side flaps which extend from the sides of said reverse member, which are of such width that they overlap each other above said reverse member when they are folded along the sides of said reverse member, and which are of such length at their lower ends that they overlap the bottom of said reverse member, when they are folded along the sides of said reverse member, the edges of said side flaps diagonally crossing each other substantially at the line confining the bottom of said reverse member, when said flaps are folded over said reverse member, and a base flap extending from the bottom of said reverse member.

7. A blank of foldable material, for a drinking cup, comprising a reverse member, the sides and bottom of which are defined, respectively, by the sides and base of a trapezoid and the top margin of which is defined by a convexly curved line, flaps extending from the opposite longitudinal sides of said reverse member, foldable transversely over said

- reverse member so that their longitudinal edges will overlap each other and form an obverse member, the bottom transverse edge of which will extend below the base line of said 5 reverse member and the top margin of which will be defined by a concavely curved line, a flap extending from the base of said reverse member, foldable longitudinally thereover to overlap the bottom transverse edge of said obverse member, and adhesive means on one side of said base flap and of those parts of said side flaps which overlap each other and said base flap when in overfolded position.
8. A blank of foldable material, for a 15 drinking cup, comprising a reverse member, the sides and bottom of which are defined, respectively, by the sides and base of a trapezoid, flaps extending from the opposite lon-
- gitudinal sides of said reverse member, foldable transversely over said reverse member so 20 that their longitudinal edges will overlap each other and form an obverse member, the bottom transverse edge of which will extend below the base line of said reverse member and the longitudinal overlapping edges of which 25 will diagonally cross each other substantially above said base line of said reverse member, a flap extending from the base of said reverse member, foldable longitudinally thereover to overlap the bottom transverse edge of said 30 obverse member, and adhesive means on one side of said base flap and of those parts of said side flaps which overlap each other and said base flap when in overfolded position.

Signed by me this 24 day of January, 1927.
MATTHEW VIERENGEL.
